UNITED STATES PATENT OFFICE

HUGO BUSCHMANN, OF MÜLHEIM-ON-THE-RUHR, GERMANY.

ADJUSTABLE SUPPORT FOR MODELS, CARDS, &c.

No. 841,372.

Specification of Letters Patent.

Patented Jan. 15, 1907.

Application filed April 27, 1906. Serial No. 314,089.

To all whom it may concern:

Be it known that I, HUGO BUSCHMANN, a subject of the German Emperor, and a resident of Mülheim, Ruhr, Germany, have invented new and useful Improvements in Adjustable Supports for Models, Cards, and the Like, of which the following is a specification.

This invention relates to an adjustable support for models, cards, and the like for school demonstrating purposes, as shown in the accompanying drawings, in which—

Figure 1 is a front view, and Fig. 2 a side view, of the support, while Figs. 3 and 4 and 3^a and 4^a, respectively, show modified forms of attachment of the support to any ordinary table or the like in front view and side view.

By means of an attachment *a*, which is fixed to the top plate of an ordinary table through the medium of clamp-screws, as shown in Figs. 1 and 2, or to a ledge provided on the table, either through the medium of a rectangular groove, as shown in Figs. 3 and 3^a, or of a dovetail-shaped groove, in which case the fastening of the attachment may be strengthened by pins *b* passed through the attachment and adapted to catch into corresponding holes provided in the table, as shown in Figs. 4 and 4^a, the support *b* is held in position.

The support *b* comprises the rigid plate *c* and the movable plate *d*, which is hinged thereto and adapted either to be folded up, so as to lie flat on the plate *c*, or to be unfolded, so as to project at right angles to the plate *c*.

The rigid plate *c* is fixed to a rod *f*, which is passed through the attachment *a* and adapted to slide therein and provided with a series of holes *h*, through which a pin *g* can be inserted so as to lie upon the attachment *a*, and thus to prevent the support from falling. By providing several holes *h* the support can be adjusted in its vertical position.

For drawing purposes in schools the mov-

able plate of the support is unfolded and any convenient article or model—such as a cylinder, cone, or the like—placed thereon.

To let the shadows of this article appear very distinctly, the plate *c*, as well as the plate *b*, is painted quite white, so that the children can draw the article or model such as appearing on the support with shadows.

To demonstrate cards, drawings, and the like, the plate *d* is folded up and held in this position by any suitable means, such as a stop or the like, (not shown in the drawings,) whereupon the cards, drawings, or the like may be suspended from a hook *e*, provided at the top of plate *c* for this purpose.

Having fully described my invention, what I claim, and desire to secure by Letters Patent, is—

Adjustable support for school demonstrating purposes, comprising in combination a rigid plate *c* painted quite white, a movable plate *d* also painted quite white and hinged to said rigid plate *c* and adapted either to be folded up so as to lie flat on said rigid plate *c* or to be unfolded so as to project at right angles to said rigid plate *c*, a hook *e* provided at the top of said rigid plate *c*, a rod *f* fixed to said rigid plate *c* and provided with a series of holes, an attachment *a* adapted to be fixed to a table or the like and to receive said rod *f* so that the latter can slide therein, and a pin *g* adapted to be inserted through one of the holes in said rod *f* so as to lie upon said attachment *a* and thus to fix said rigid plate *c* to any desired height, substantially as described and shown and for the purpose set forth.

In testimony whereof I have hereunto set my hand in the presence of two subscribing witnesses.

HUGO BUSCHMANN.
